ATTORNEY.

UNITED STATES PATENT OFFICE.

JOHN J. McLOUGHLIN, OF PHILADELPHIA, PENNSYLVANIA.

PANTALETS AND SIMILAR GARMENT.

Application filed August 2, 1923. Serial No. 655,173.

To all whom it may concern:

Be it known that I, JOHN J. McLOUGHLIN, a citizen of the United States, residing at Philadelphia, county of Philadelphia, and 5 State of Pennsylvania, have invented a new and useful Improvement in Pantalets and Similar Garments, of which the following is a full, clear, and exact description, reference being had to the accompanying drawings, which form a part of this specification.

My invention is applicable to pantalets, bloomers, drawers, etc., and has for its object to enhance the wearing qualities of the garment, provide for flexibility at the localities 15 where, in use, stretching strains are most pronounced, and promote the comfort of the wearer.

It is recognized that the localities of greatest wear and stress are in the neighborhood 20 of the crotch and it is customary to strengthen this part of the garment by reinforcing linings or by inserts of extra thickness. This has involved the presence of seams at, or in the vicinity of, the crotch, 25 These seams are an element of weakness, especially at the point where two or more seams join, besides impairing flexibility in the particular locations subject to the greatest stress and strain and which, therefore, 30 should be particularly flexible.

The objections to the present methods of construction are entirely overcome by my invention, which, however, involves the sacrifice of no essential advantage resulting 35 from reinforcements and inserts. A preferred embodiment of the invention is shown in the accompanying drawings, in which—

Fig. 1 is a front view of the garment.

Fig. 2 is the blank which forms the median section of the garment and

Figs. 3 and 4 are the blanks which form the remainder of the garment.

The garment illustrated comprises three sections, namely: side sections *a* and *b*, each 45 of which make up one side of the body and the major part of the corresponding leg; a single median section forming the front *c* and rear *d* of the body, the inside parts *e* and *e* of the legs and the crotch portion *g* 50 of the garment; and which may be provided with a reinforcing element or lining that may be coincident in dimensions with the median section, but preferably does not extend to the top of the front portion of the 55 garment, so that the major portion of the median section is two ply.

By reference to Fig. 2, it will be observed that the median section is shaped, roughly, like a cross, two opposite branches *c* and *d* being relatively broad and the other two opposite branches *e* and *e* being relatively narrow and tapering toward their ends. Adjacent edges of adjacent branches of the cross are connected together by curves of considerable radii. 65

The reinforcing has the same shape and size as the median section except that the branch corresponding to branch *c* of the median section is preferably quite short. The branch corresponding to branch *d* of 70 the median section may also be shortened or lengthened more or less, if desired.

In securing the sections together, the reinforcing is applied to the back of the median section, and the edges of both these elements 75 forming the median sections are secured to the edges of the side sections *a* and *b*, forming the four seams *w*, *x*, *y*, *z*. The reinforcing element is also sewed to the outer or main element of the median section along the 80 line *v*—*v*.

Constructed as described, the pantalet has the following advantages. The locality subject to the greatest wear, and particularly to the greatest stresses and strains, is the 85 crotch portion of the garment, which includes the center of the "cross" and an area surrounding such center. In my improved construction, this area is of double thickness to resist wear but is entirely devoid of any 90 seams. Seams not only prevent ready flexure, but they are necessarily the weakest part of the garment and where they are located at or near the crotch, they invariably rip or tear long before the remainder of the garment has ceased to be entirely serviceable. 95 In my improved construction, the seams are located along lines where flexibility is not especially required and where there are no special stresses or strains. The provision for flexibility in the crotch portion is also advantageous in that it conduces to the comfort of the wearer.

Another advantage of my construction is its superior simplicity in that the entire 105 garment (excluding the reinforcement or lining) comprises only three pieces, namely: two side sections and a single median section. The cutting of patterns and the sewing together of the parts are therefore much simplified. 110

Having now fully described my invention,

what I claim and desire to protect by Letters Patent is:

1. A garment having legs and a body portion, comprising two spaced substantially identical sections and an inserted cross-shaped section secured to the side edges of said two sections respectively to form a seamless crotch.
2. A garment having legs and a body portion, comprising three sections secured together adjacent their edges, two of the sections being spaced throughout a substantial portion of the body and forming opposite sides of the body and portions of the legs of the garment, the third section being cross-shaped and being secured to the side edges of the other sections to complete the body and legs of the garment and form a seamless crotch.
3. A garment, having legs, a body portion and a seamless crotch, comprising three sections, one of said sections being cross-shaped and forming the intermediate front and rear

portions of the garment, the inside portion of the legs and crotch, the other two said sections being substantially identical and being secured at their side edges to the edges of the other section and forming the sides of the body of the garment and the outside portions of the legs.

21

30

4. A garment having legs, a body portion and a seamless crotch, comprising three sections, one section being cross-shaped, the others substantially identically shaped, the side edges of each of the two sections being secured to both side edges of an arm of the other section and to one edge of each of the other arms, there being four seams at the junctions of the sections, each seam extending from the belt line to the lower end of a leg.

40

In testimony of which invention, I have hereunto set my hand, at Philadelphia, Pa., on this 30th day of July, 1923.

JOHN J. McLOUGHLIN.
